UNITED STATES PATENT OFFICE.

WILLIAM A. WILLIAMS, OF COLUMBUS, OHIO.

ELEVATOR-DOOR LATCH.

Application filed March 22, 1922. Serial No. 545,879.

To all whom it may concern:

Be it known that I, WILLIAM A. WILLIAMS, a citizen of the United States, residing at Columbus, in the county of Franklin and State of Ohio, have invented a certain new and useful Improvement in Elevator-Door Latches, of which the following is a specification.

The object of this invention is to provide for the door of an electrically operated elevator an improved safety latch of the kind requiring complete and effective closing of the door before the car can be started. Other objects will appear from the following description.

The invention is embodied in the example herein shown and described, the features of novelty being finally claimed.

In the accompanying drawing—

Figure 1 is a vertical sectional view showing the latch about to close with the electric circuit broken.

Fig. 2 is a similar view showing the latch latched and the electric circuit closed.

Fig. 3 is a transverse view of the circuit closing box.

Fig. 4 is a plan view of the circuit closing member.

In the views 5 designates the circuit closing box, which is to be mounted at one of the upper corners of the door frame. Said box is of metal with removable sides that have linings 6 of mica. The top also has a lining of mica on which is superposed a fibre electrode holder 7 of insulating material. The part 7 is held up by tongued and grooved end linings 9 and 10. The end linings are interchangeable and one only need be perforated as shown at 9^a to admit the wires 24 of the elevator operating electric circuit. The upper side is provided with a layer of fibre insulating material 8 and said cover is hinged at 12, its insulating cover 8 projecting to form a stop to catch against the strike or keeper 5^a of the case. The cover 8 is made thick enough so that the interior of the case is after installation at no time exposed to admit dirt or other matters adapted to interfere with the proper and successful operation of the circuit closer.

The circuit closer consists of a strip of metal 13 mounted slidably on a post 14 on the upper side of the cover and held up by a spring 14^a against a cross pin 15 in the upper end of the post. The electrodes 16 of

the operating circuit are secured to posts 17 secured on the upper insulating member. Because the circuit closer is moved in an arc having for its center the hinge 12 of the cover it contacts with the electrodes with a rubbing contact and so keeps those contacts clean and insures effectiveness in closing the circuit.

Several inlets for current conducting wires 24 to the box are shown so as to provide for differences in installation conditions. Those inlets not used can be closed with threaded plugs as shown at 18. The circuit wires 24 are carried to the box 70 through the usual protecting pipe 23 connected to one of said inlets.

The door latch bolt 19 is provided with an anti-friction roller 20. This bolt is mounted in a suitable case 21 to be secured to the elevator door. The bolt 19 is normally pressed upward, as usual, by a coil spring 22 within the bolt case. The bolt extends down to a point within easy reach of the elevator operator where it is provided with a suitable handle (not shown) for depressing it, as usual, when the door is to be opened.

In operation when the door is slid to the left to close the bolt strikes the inclined keeper lip 5^a and as it passes the keeper 5^a it is thrown down. After passing said keeper the bolt engages the cover and throws it up as shown in Fig. 2 thereby latching the door and at the same time closing the elevator operating circuit. The construction is such therefore that the elevator car cannot be moved unless the door is completely latched and the power circuit closed.

Should any of the parts become loose and detached within the box there is no danger of such parts diverting or grounding the circuit and causing fire, shocks or alarm because the interior of the box is insulated.

It will be noted that screws to fasten the top and end insulation are employed and that when the micaed sides are secured to the case the top and end insulations are secured from removal. The end and top insulations can be removed by removing one of the side walls.

The forms of the parts can be changed without departing from the gist of the invention as claimed.

What I claim is:

1. A latch case for an electric elevator door comprising, in combination, a box-like

2
structure, electrodes for an elevator operating circuit therein, said structure having a hinged cover carrying a spring-held circuit closer for said circuit and means for limiting the outward movement of said cover to prevent the exposure of the interior of said case.

2. A latch case for an electric elevator door comprising, in combination, a box-like structure having a keeper projection at one end, electrodes for an elevator operating circuit therein, said structure having a hinged cover carrying a spring held circuit closer for said circuit and means for limiting the outward movement of said cover to prevent the exposure of the interior of said case.

3. A latch case for an electric elevator

door comprising, in combination, a box-like structure, electrodes for an elevator operating circuit therein, a hinged cover carrying a spring held circuit closer for said circuit, and insulating linings for the interior of said box-like structure and said cover.

4. In a latch device for an electric elevator door, in combination, a box-like structure, electrodes for an elevator operating circuit therein, said structure having a hinged cover carrying a spring-held circuit closer for said circuit, and means for limiting the movement of said cover adapted to prevent the exposure of the interior of said structure in both the circuit-opened and circuit-closed positions of the cover.

WILLIAM A. WILLIAMS.
